(57) **CLAIM**

The ornamental design for the rearview mirror and bezel assembly, as shown and described.

DESCRIPTION

FIG. 1 is a top, front perspective view of a rearview mirror and bezel assembly showing our new design; FIG. 2 is a bottom front perspective view of the embodiment of FIG. 1;

FIG. 3 is a front elevation of the embodiment of FIG. 1; FIG. 4 is a top plan view of the embodiment of FIG. 1; FIG. 5 is a bottom plan view of the embodiment of FIG. 1; FIG. 6 is a right side elevation of the embodiment of FIG. 1;

FIG. 7 is a left side elevation of the embodiment of FIG. 1; FIG. 8 is a top, front perspective view of a second embodiment of the rearview mirror and bezel assembly showing our new design;

FIG. 9 is a bottom front perspective view of the embodiment of FIG. 8;

FIG. 10 is a front elevation of the embodiment of FIG. 8; FIG. 11 is a top plan view of the embodiment of FIG. 8; FIG. 12 is a bottom plan view of the embodiment of FIG. 8; FIG. 13 is a right side elevation of the embodiment of FIG. 8; and,

FIG. 14 is a left side elevation of the embodiment of FIG. 8. The broken lines showing a rearview mirror housing are for illustrative purposes only and form no part of the claimed design.
